UNITED STATES PATENT OFFICE.

ALFRED G. F. KUROWSKI, OF BROOKLYN, NEW YORK, ASSIGNOR TO UNDERWOOD
TYPEWRITER COMPANY, OF NEW YORK, N. Y., A CORPORATION OF DELAWARE.

TYPEWRITING MACHINE.

Application filed August 18, 1924. Serial No. 732,772. 55
This invention relates to machines for 10 typing address-stencils, and particularly to machines of the class wherein the stencil is fed to the printing point by means of a 15 stencil-carrying frame arranged to grip the stencil and to be progressively raised step by step to line-space the same. A machine of this character forms the subject of the 20 patent to S. Elliott, No. 1,378,771, granted 25 May 17, 1921. 30
The present invention is directed to an improvement in the carriage and type-bar segment of the platen to receive the type-impressions. 35
Other features and advantages will hereinafter appear. 40
In the accompanying drawings, 45
Figure 1 is a transverse section of the carriage and type-bar segment of a type-writing machine, taken on the line 1—1 of Figure 4, and showing the features embodying the present invention applied to the 50

10 patent to S. Elliott, No. 1,978,111, granted
May 17, 1921.

The machine disclosed in said Elliott patent is provided with a stencil-carrying frame which overlies the machine, and is pivoted at a point on the carriage far to the rear of the printing point of the platen, and is provided with clamping jaws to grip a stencil by its upper margin and then present the stencil to the printing field. The stencil-carrying frame shown in this mechanism is arranged to be lifted to line-space the stencil by means of a turning knob operating a cam-and-ratchet mechanism mounted on the stencil-carrying frame, said cam-and-ratchet mechanism co-operating with means supported by the carriage to feed the stencil step by step to the printing line.

It is one feature of the present invention to utilize certain of the above-indicated features while providing a stencil-carrying frame, the construction of which is such that, when the frame is thrown back and the carriage shifted upon the rails, there will be no tendency of the stencil-carrying frame to overbalance the carriage toward the rear of the machine.

Another feature of the invention is the provision of a simplified bracket, which functions as a supporting means for a carbon-paper receptacle and carries a stop for limiting the rearward position of the stencil-carrying frame when thrown back out of operation.

A further feature embodies a guard device which is effective to retain the carbon-paper roll within its receptacle, the arrangement being such, that a roll may be quickly and easily inserted or withdrawn therefrom.

50 In accordance with a further feature of the invention, a novel deflector-plate is attached to the type-bar segment to cause the stencil to be properly positioned in front

of the platen to receive the type-impressions.

Other features and advantages will hereinafter appear.

In the accompanying drawings, Figure 1 is a transverse section of the carriage and type-bar segment of a type-writing machine, taken on the line 1—1 of Figure 4, and showing the features embodying the present invention applied to the machine.

Figure 2 is a front elevation of a deflector-plate for the stencils.

Figure 3 is a view showing the bracket support and guard device for the carbon-

Figure 4 is a plan view of the machine 70

Figure 1 is a plan view of the machine, with the mechanism comprising the invention shown thereon.

Referring with particularity to Figures 1 and 2 of the drawings, reference numeral 10 indicates a type-bar mounted on a type-bar segment 11 to swing upwardly and rearwardly to cause its type 12 to strike a cylindrical platen 13, which is journaled by a shaft 14 in the ends of the platen-frame 15. The usual hand-wheel 16 is provided upon the shaft 14. The platen-frame is

mounted on a carriage 17 and travels therewith upon the usual carriage rails (not shown). A stencil-card 18 is arranged to receive the impressions of the type 12, and is held within the printing field by means supported upon and moving with the carriage of the machine, said means comprising fixed jaws 19 carried by a stencil-frame 20.

and jaws is carried by a stencil frame 20 and co-operating with pivoted jaws 21 operated by a handle 22 to clamp the upper margin of the inserted stencil-card 18. A stationary handle 23 is provided upon the frame 20 and is grasped to aid in operating the handle 22 to adjust the stencil-card to position between the jaws. A shaft 24 is

journalized on the stencil-frame 20, and may be rotated by means of a suitable finger-wheel 25 to turn a cam 26 which rests upon a fixed roller 27, the latter carried upon a member 28 having a hub 29 by means of which said member is mounted upon a

rod 30 and secured against movement thereon. The ends of the rod 30 are secured to ears 31 forming a part of a pair of end plates 32 and 33. Thus, when the finger-

wheel 25 is rotated, the frame 20 rises and thereby feeds the stencil to the printing field, and a pawl 34 engages a ratchet-wheel 35 fast to the shaft 24 to control the feed 5 of the stencil-card, step by step.

A coil spring 36 encircles the rod 30 and is effective to cause a roller 37 journaled in a forward extension 38 of a yoke 39 to hold a strip of carbon-paper 37' pressed against 10 the platen 13, and a handle 40, associated with the yoke, serves to lift the roller from the platen when so desired. The stencil-frame 20 comprises a pair of arms 41 joined together by a yoke-piece 42 upon a rod 43 15 disposed at the rear of the machine and extending parallel with the platen-shaft, the ends of the rod being milled flat and secured by suitable screws 44 to extensions 45 and 46 of the end plates 32 and 33, respectively. It will be noted that the rod 43 is positioned well in toward the platen, so that when the stencil-frame is thrown back and stopped, to occupy the position indicated by 20 dotted lines in Figure 1, the center of weight of the frame will be close to the carriage. Thus, there will be no tendency of overthrowing the carriage toward the rear of the machine, such as would occur, if the frame were so constructed as to occupy a 25 position far out from the back of the carriage when swung backwardly therefrom.

A carbon-paper receptacle 47 is positioned underneath the stencil-frame, and comprises a sheet of metal curved to form 30 an open-ended cylinder, having a slot 48 through which the paper is threaded from a roll of carbon-paper 49. A bracket 50 is formed at its lower end with a boss 51, which is drilled out so as to be received upon 35 the rod 43, and is secured thereto by means of set-screws 52, so that the bracket will be stationary with the rod. A horn-shaped extension of the boss 51 provides a stop 53, which lies in the path of movement of the 40 yoke-piece 42 of the frame 20 when the latter is thrown back about its pivot, and acts as a limiting means to govern the rearward position of the stencil-frame. The upper 45 end of the bracket is curved and fastened 50 to the receptacle 47 by soldering, or in any other manner found desirable.

Means are provided for retaining the paper-roll 49 within the receptacle 47, and comprises a length of spring wire 54 fastened upon the top of the bracket 50 adjacent the receptacle 47 and held to the bracket by means of a screw 55, so as to provide a pair of fingers 56 and 56'. The fingers 56 and 56' extend from the bracket in opposite directions along the back of the receptacle, to a point slightly beyond the ends of the receptacle where they are bent substantially at right angles, as shown in Figures 55 3 and 4, and formed with loops 57 to overlie 60 the open ends of the receptacle 47. It is ob-

vious that a carbon-roll may be inserted or withdrawn from the receptacle by simply moving the free end of the finger 56' away from the end of the receptacle, as illustrated in Figure 3.

In typing stencil-cards upon an ordinary typewriting machine, it is customary to provide a backing for the cards, so as to prevent the type blows from injuring the platen. A device of this nature is disclosed in 70 my pending application, Serial No. 708,332, filed April 23, 1924, and need not be described in detail in the present application, as it forms no part of the present invention. The backing consists generally of a 75 sheet of celluloid or similar material 58 encircling the platen, which is held in place thereon by means of a holder-plate 59. Mechanism including a pair of pins 60 carried by one end of the platen engages 80 notches in a stop device 61 when the platen is turned and limits the movement thereof.

When it is desired to print upon the back of the stencil-cards, the carbon-paper 37' is led through the slot 48 down around the 85 platen, and under the roller 37 through a guide 62, and thence upwardly over the top of the receptacle 47, and, upon operating the handle 22 to release the roller 37 from the paper, an unused area of carbon-paper 90 may be fed beneath the card by grasping the free end of the paper and drawing it around the platen.

For the purpose of assisting in guiding the stencil to position around the platen, 100 provision may be made of a deflector-plate 63 mounted by fingers 64 upon the type-bar segment 11 by means of suitable screws 65. This deflector-plate may be formed of a single piece of sheet-metal, and is notched out at 66 to provide clearance for the type-bars when driving their type through a type-guide 67 and against the stencil-card 18. The deflector-plate is curved forwardly and downwardly so as to engage the lower portion of an inserted stencil-card, and press 110 it toward the platen, and thereby assure the stencil being held against the platen at the typing point. The deflector-plate is of a length sufficient to extend well over both 115 ends of the inserted card, and it will be noted that the major portion of the card is in contact with the curved portion of the deflector-plate, the card being thus securely held in position. Also, due to this construction, the cards may be moved to or removed 120 from printing position without danger of the deflector-plate catching onto the margins of the cards.

Variations may be resorted to within the 125 scope of the invention, and portions of the improvements may be used without others.

Having thus described my invention, I claim:

1. In a typewriting machine for impress-

ing characters on stencils, in combination, a platen, a carriage, a set of types, a rod carried upon the rear of the carriage, a stencil-holding frame, including a pair of stencil-gripping arms and a yoke joining said arms, pivoted upon the rod to swing rearwardly of the carriage, and a stop carried by the rod and lying in the path of said yoke to engage the same for limiting the throw of said frame when swung rearwardly about its pivot, and thereby preventing the weight of the frame from overbalancing the carriage.

2. In a machine for impressing characters on stencils, in combination, a platen, a carriage, a set of types, a rod secured to the carriage at the rear of the machine and extending parallel with the platen-shaft, a stencil holding frame including a pair of arms and a yoke joining the arms, pivoted upon the rod, and a stop member fixed to the rod, so that, when the frame is swung from normal position to the rear of the machine, said stop member engages the yoke to limit the rearward position of the frame.

3. In a machine for impressing characters on stencils, in combination, a platen, a carriage, plates on said carriage, a set of types, a rod extending parallel with the platen-shaft at the rear of the machine and having the ends thereof secured to said plates, a stencil-holding frame, including a pair of stencil-holding arms and a yoke, pivoted to swing upon the rod, and arranged to present the stencil to the printing field of the platen, to receive type impressions, and a stop member fixed to the rod, so as to be in the path of movement of the yoke, to engage the same when the frame is swung to the rear of the machine, and thereby limit the rearward position of said frame with respect to the carriage.

4. In a machine for impressing characters on stencils, the combination with a carriage and a platen thereon, of a hollow receptacle having both ends open and arranged to contain a roll of carbon-paper in strip form, so as to be fed around the platen, and resilient means overlying both of the ends of said receptacle for retaining the roll therewithin.

5. In a machine for impressing characters on stencils, the combination with a carriage and a platen thereon, of a hollow cylinder having both ends open and arranged to contain a roll of carbon-paper in strip form, so as to be fed around the platen, and resilient spring wire members positioned so as to overlie the ends of said cylinder to retain the roll therewithin said members being movable to permit said roll to be inserted or withdrawn from the cylinder.

6. In a machine for impressing characters on stencils, in combination, a carriage, a platen thereon a bracket mounted on the car-

riage, a hollow cylinder carried by the bracket, said cylinder having both ends open and being arranged to contain a roll of carbon-paper in strip form, so as to be run around the platen, and means mounted upon the bracket, so as to overlie the open ends of the cylinder for retaining said roll within said cylinder.

7. In a machine for impressing characters on stencils, in combination, a carriage, a platen thereon, a bracket mounted on the carriage, a hollow cylinder carried by the bracket, said cylinder having both ends open and being arranged to contain a roll of carbon-paper in strip form, so as to be run around the platen, and a pair of resilient spring members secured to the bracket so as to overlie the ends of the cylinder to retain the roll therewithin, one of said spring members being movable to permit insertion or withdrawal of the roll from the cylinder.

8. In a machine for impressing characters on stencils, in combination, a platen, a carriage, a rod secured upon the rear of the carriage, a stencil-holding frame pivoted upon the rod so as to be swingable rearwardly of the carriage, a receptacle for holding a roll of carbon-paper in strip form to be fed around the platen, and a bracket mounted upon the rod for both supporting said receptacle and acting as a stop for limiting the rearward swing of the frame.

9. In a machine for impressing characters on stencils, in combination, a platen, a carriage, a rod secured upon the rear of the carriage and extending parallel with the platen-shaft, a stencil-holding frame pivoted upon the rod, so as to be swingable to the rear of the carriage, a receptacle for holding a roll of carbon-paper in strip form to be fed around the platen, and a bracket secured upon the rod, said bracket including an extension for supporting the receptacle, and a stop for engaging a portion of the frame to limit the position thereof when swung rearwardly of the machine.

10. In a machine for impressing characters on stencils, in combination, a platen, a carriage, a rod secured upon the rear of the carriage and extending parallel to the platen-shaft, a stencil-holding frame, including a pair of stencil-holding arms and a yoke, pivoted upon the rod, so as to be swingable rearwardly of the carriage, a receptacle for holding a roll of carbon-paper in strip form to be fed around the platen, and a bracket including an extension for supporting the receptacle, and a stop member disposed in the path of movement of the yoke to engage the same for limiting the position of the frame when swung rearwardly about its pivot and thereby prevent overbalancing of the carriage.

11. In a machine for impressing characters on stencils, in combination, a platen, a car-

riage, end plates on the carriage, a rod extending parallel with the platen-shaft at the rear of the machine and having the ends thereof flattened and secured to the end plates, a stencil-holding frame including a pair of stencil-holding arms disposed transversely over the carriage, and thence directed downwardly over the rear thereof where they are pivoted upon said rod and joined together by a yoke, which underlies the rod, and an ear secured to the rod, so as to be in the path of movement of the yoke, so that, when the frame is being swung to the rear of the machine, said ear engages the yoke thereby acting as a stop for determining the rearward position of the frame.

12. In a machine for impressing characters on stencils, the combination with a carriage and a platen thereon, of an open-ended receptacle for containing a roll of carbon-paper in strip form and having a slot in the side thereof through which said strip is fed, so as to be run around the platen, a bracket associated with the carriage and upon which said receptacle is mounted, and a resilient spring member secured to the bracket at one side of the receptacle and having fingers extending adjacent said side in opposite directions to the ends of the receptacle, where they are bent substantially at right angles to overlie said ends for retaining the roll within its receptacle.

13. In a machine for impressing characters on stencils, the combination with a carriage and a platen thereon, of an open-ended receptacle for containing a roll of carbon-paper in strip form and having a slot in the side thereof through which said strip is fed, so as to be run around the platen, a bracket associated with the carriage for mounting the receptacle, and a length of spring wire secured intermediate its extrem-

ities to the bracket to form fingers which extend adjacent one side of the receptacle in opposite directions to a point slightly beyond the ends of the receptacle, where they are bent substantially at right angles and formed with loops to overlie the ends of the receptacle whereby to retain the roll therewithin, and, due to their resiliency, said fingers being movable away from said ends to permit the insertion or withdrawal of a carbon-roll.

14. In a typewriting machine for impressing characters on stencils, the combination with a platen and stencil-holding means for gripping a stencil by its upper margin and presenting the same to the printing line, of a deflector-plate adjacent the front of the platen, the stencil being inserted between the plate and the platen and then moved to typing position, said plate engaging the entire outer area of that portion of the stencil extending below the printing line and effecting a flexing of said portion downwardly and toward the platen, so as to maintain said stencil firmly against the platen at said printing line.

15. In a typewriting machine for impressing characters on stencils, the combination with a platen, a type-bar segment, and stencil-holding means for gripping a stencil by its upper margin and moving the same to the printing line, of a stencil-deflector closely adjacent the front of the platen, and including fingers for attachment to the type-bar segment and a plate curved forwardly and downwardly toward the platen for engaging the stencil over the area thereof extending below the printing line, so as to securely hold said stencil against the platen at said printing line.

ALFRED G. F. KUROWSKI.
